UNITED STATES PATENT OFFICE.

LEE S. BURRIDGE, DECEASED, LATE OF NEW YORK, N. Y., BY FRANCIS O. BURRIDGE, EXECUTOR, OF NEW YORK, N. Y., ASSIGNOR, BY MESNE ASSIGNMENTS, TO UNDERWOOD TYPEWRITER COMPANY, OF NEW YORK, N. Y., A CORPORATION OF DELAWARE.

TYPE-WRITING MACHINE.

1,310,000.

Specification of Letters Patent. Patented July 15, 1919.

Original application filed September 27, 1915, Serial No. 52,594. Divided and this application filed October 30, 1917. Serial No. 199,237.

To all whom it may concern:

Be it known that LEE S. BURRIDGE, deceased, late a citizen of the United States, and late residing in the borough of Manhattan, county, city, and State of New York, invented certain new and useful Improvements in Type-Writing Machines, of which the following is a specification.

This invention relates to typewriting machines, and more particularly to means for controlling the margin of the work-sheets, especially in connection with adjustable fingers or devices to hold the work-sheet against the platen.

15 This application is a division of pending application No. 52,594, filed September 27, 1915.

According to the present invention, in addition to holding the work-sheet close to the platen, the paper-finger device for one side of the sheet has also means to warn the operator when the end of the line of writing has been reached. When this finger is adjusted to position at the side margin of the 25 work-sheet, an alarm device for warning the operator is simultaneously adjusted therewith.

As matters of further improvement, the paper-guiding fingers, which are stamped from sheet-metal, are loosely mounted upon carriers which are slidably mounted upon a rack which extends from side to side of the typewriter carriage. This rack is made of thin sheet-metal and is secured to a small 30 rail, which, in turn, is secured to the typewriter carriage frame. The carriers are also stamped from sheet-metal, and each of them has two bent ears which hook over the rack. The carrier for the right-hand margin finger is provided with a projection or 35 tappet, which, when the typewriter carriage is moved to the left, strikes a clapper and rings a bell which warns the operator that the end of the line has been reached. 40 Each paper-finger and carrier is normally locked against lateral movement by a tooth thereon, which normally extends into one of the notches of the rack. To free these devices from the rack for lateral movement, 45 a finger-piece is provided upon each, which, when depressed, causes the locking tooth thereon to become disengaged from the rack. When the finger-piece is depressed

and moved sidewise toward the desired position, the paper-finger tilts and binds the 55 carrier. This binding action causes the locking tooth to remain out of engagement with the rack without the operator maintaining the downward pressure upon the finger-piece. A spring normally holds the 60 paper-finger and the locking tooth up in engagement with the rack.

It will be apparent that the paper-finger may also be adjusted along the supporting rail, without the necessity of first depressing 65 the same to free its locking tooth from its engagement with said rack. In view of the arrangement and co-operative relation of the parts disclosed, the finger may be adjusted from one point to another by merely applying a pressure at the end of the paper-finger in the direction of its movement of adjustment. This will first cause the paper-finger to be slightly rotated or tilted about 70 one end of its base to such an extent as to 75 free its locking tooth from the rack, after which a continuation of such pressure will cause the paper-finger to be moved bodily in its direction of adjustment.

Other features and advantages will here- 80 inafter appear.

In the accompanying drawings,

Figure 1 is a front view, showing the present invention attached to the typewriter carriage.

Fig. 2 is a sectional side elevation of the same.

Fig. 3 is a front detail view of the combined margin regulator and marginal paper-finger.

Fig. 4 is a sectional side elevation, showing the bell and clapper and the margin regulator.

Type-bars 10 strike upwardly and rearwardly against the front face of a platen 11, 95 mounted on a shaft 12, journaled in the carriage, which comprises side plates 13 and transverse rails 14.

The carriage travels in letter-feed and return directions upon ball-bearings 15 which 100 are arranged between the rails 14 and shaped plates 16. The carriage is connected by a cord 17 to a spring drum 18.

The carriage escapement mechanism comprises an escapement wheel 19 connected to 105 a pinion 20 meshing with a carriage rack

21. Dogs 22 are carried by a rocker 23 controlled by the keys. From the usual shelf 24 the sheets are fed around the platen 11 by a roll 25. Springy paper-fingers 26 bear 5 upon each side-margin of the sheet. They are of inverted Y-shape, with bent finger-pieces 26^a at the upper ends. Each finger or clip is carried by a plate 27 (see Fig. 4), which is slidable along a scale plate 28 for 10 adjustment. The scale plate 28 is carried by a narrower bar 29, which, in turn, is secured to the side plates 13 of the carriage frame. The paper-fingers 26 extend across the line of writing and are curved to conform 15 to the periphery of the platen.

The sliding carrier in each case has two upstanding guiding and supporting-fingers 30, which lie against the face of the scale, and are crimped around its top edge. The 20 carrier 27 is also turned under the scale and has an offset 30^a (Fig. 4) behind the lower edge of the same.

A locking tooth 32, extending from a piece 33 which connects the lower branches 25 of the paper-finger, coöperates with the teeth of a rack 34 provided on the lower edge of the scale 28.

In order to release the tooth 32, the piece 33 with the paper-fingers 26 is mounted for 30 movement up and down on the carrier 27. The piece 33 is turned under the carrier 27 (see Fig. 2), and there has an opening 35 through which passes a downwardly-extending finger 36 which is formed from part of 35 the carrier. The finger 36 serves as a support for a spring 37, the upper end of which bears against the plate 33, and is held by a projection 38 on the latter. This spring normally holds the finger-plate up against its 40 carrier with the tooth 32 engaging the rack.

To shift a paper-finger across the machine, the finger-piece 26^a may be depressed against the tension of spring 37, disengaging the tooth from the rack 34, and freeing the 45 carrier 27. The paper-finger 26 is guided in this downward movement on the carrier by means of pins 39 mounted upon the carrier and passing through openings 40 on the piece 33. The pins are of such length as to 50 always lock the finger 26 to the carrier for longitudinal movement.

When the finger-piece 26^a is depressed, it 55 may be slidden along with the carrier by a simple push or pull movement, without maintaining downward pressure on the finger-piece, because of a clamping action between the paper-finger and the carrier. For this purpose the pins 39 are sufficiently loose in the holes 40 to permit the finger to be 60 tilted when the tooth 32 is out of the rack, until the part 33 of the finger 26 binds with the carrier at such an angle as to keep the tooth 32 from reengaging the rack 34, so long as the push or pull pressure is maintained upon the finger-piece 26^a of the fin-

ger 26. When this pressure is released from the paper-finger, the spring 37 causes the part 33 to be released from the carrier, and the tooth 32 is permitted to again engage the rack 34.

Although the paper-finger may be adjusted from one point to another by first depressing the same at the finger-piece 26^a and then moving it along its support, as above described, it is also capable of being moved 70 from one point to another in a somewhat different manner. In view of the arrangement and coöperative relation of the parts of the mechanism herein disclosed, the finger may be adjusted by a simple application of 75 pressure at its end, and in the direction of its movement along its support. The effect of such application of pressure would be such as to first impart a slight rotation or tilting movement of the paper-finger in the 80 plane of its movement alongside the platen. This tilting movement would free the tooth 32 from the teeth of the rack 34, after which, on a continuation of such pressure in the 85 same direction, the finger might be moved 90 to its adjusted position.

The paper-finger is provided with an index-piece 42 which registers with the graduations 41 on the scale plate 28.

On the front plate 16 of the platen frame 95 is a margin alarm or bell 43. A clapper 44 is mounted on a pin 45 loosely supported or floated by a coiled spring 46, which, at one of its ends, is supported on a pin 47 on the rear cross-plate 16 of the platen frame. The 100 clapper pin 45 projects through an opening 48 in the front cross-plate 16 of the platen frame, and lies in the path of a finger 31 on the carrier 27 of the right-hand paper-finger.

The carriage spaces step by step across the 105 machine, and when the end of the line is reached, the finger 31 first tensions the spring 46, and then releases the clapper 44, so that the clapper strikes the bell to sound the alarm. From this it will be seen that 110 the time of the sounding of the alarm is dependent upon the adjustment of the paper-finger for the right-hand side of the platen, and that it is only necessary for the operator in setting the fingers to see that the 115 fingers bear on the work-sheet at the side margins.

The paper-finger and the combined paper-finger and line-end alarm are simple and 120 inexpensive to make, both paper-finger and carrier being stamped from sheet-metal and bent to form. The bell-clapper is also inexpensive to make, being simply a metal sphere through which the pin 45 extends, said pin being fastened to one end of a 125 spring and being thus held in proper position and free to move in any direction.

Variations may be resorted to within the scope of the invention, and portions of the improvements may be used without others. 130

Having thus described my invention, I claim:

1. In a typewriting machine, a platen, a rail extending lengthwise of the platen and movable therewith in letter-feed and reverse directions, a marginal paper-finger carrier 5 slideable on said rail, a paper-finger movable on said carrier transversely of the rail, a rack extending lengthwise of the rail and movable therewith, and a tooth on the paper-finger, shiftable into and out of the rack by said transverse movement of the paper-finger, for holding the paper-finger and its carrier in any adjusted position along the 10 rail.
2. In a typewriting machine, a platen, a rail extending lengthwise of the platen and movable therewith in letter-feed and reverse directions, a marginal paper-finger carrier 15 slideable on said rail, a paper-finger movable on said carrier transversely of the rail, a rack extending lengthwise of the rail and movable therewith, a tooth on the paper-finger, shiftable into and out of the rack by 20 said transverse movement of the paper-finger, for holding the paper-finger and its carrier in any adjusted position along the rail, and a spring for normally holding the 25 paper-finger on the carrier with the tooth 30 in engagement with the rack.
3. In a typewriting machine, a platen, a rail extending lengthwise of the platen and movable therewith in letter-feed and reverse directions, a marginal paper-finger carrier 35 slideable on said rail, a paper-finger movable on said carrier transversely of the rail, a rack extending lengthwise of the rail and movable therewith, and a tooth on the paper-finger, shiftable into and out of the rack 40 by said transverse movement of the paper-finger, for holding the paper-finger and its carrier in any adjustable position along the rail, the carrier and paper-finger being in pin-and-slot engagement to maintain the 45 same interlocked for movement together and to guide the paper-finger in its transverse movements on the carrier.
4. In a typewriting machine, a platen, a rail extending lengthwise of the platen and 50 movable therewith in letter-feed and reverse directions, a marginal paper-finger carrier slideable on said rail, a paper-finger movable on said carrier transversely of the rail, a rack extending lengthwise of the rail and 55 movable therewith, and a tooth on the paper-finger, shiftable into and out of the rack by said transverse movement of the paper-finger, for holding the paper-finger and its carrier in any adjusted position 60 along the rail, the carrier and paper-finger being in pin-and-slot engagement to maintain the same interlocked for movement together and to guide the paper-finger in its transverse movements on the carrier; said 65 pin-and-slot engagement being sufficiently
- loose to permit the paper-finger to be tilted on the carrier to be bound therewith when the tooth is disengaged from the rack, so that such disengagement may be maintained and the carrier and finger be slid along the 70 rail by pressure on the paper-finger lengthwise of the rail.
5. In a typewriting machine, a platen, a rail extending lengthwise of the platen and movable therewith in letter-feed and reverse 75 directions, a marginal paper-finger carrier slideable on said rail, a paper-finger movable on said carrier transversely of the rail, a rack extending lengthwise of the rail and movable therewith, a tooth on the paper-finger, shiftable into and out of the rack by 80 said transverse movement of the paper-finger, for holding the paper-finger and its carrier in any adjusted position along the rail, and means operable by pressure lengthwise of the rail for maintaining the tooth and rack disengaged and for simultaneously 85 sliding the carrier along the rail.
6. In a typewriter, the combination with a platen, a traveling carriage for type-spacing said platen, and a guide-frame for said carriage comprising front and rear carriage-supporting members, of a line-end alarm comprising a bell mounted between 90 said members, a clapper for said bell, a support for said clapper, comprising a resilient member secured at one end to one of said carriage-supporting members and having its clapper-supporting end passed through an opening in said bell, a line-end- 95 determining finger carried by said carriage, and a tappet carried by said bell-clapper and projecting into the path of said finger, so as to be engaged and released thereby to ring said bell when said carriage reaches 100 the line-end position determined by the position of said finger on said carriage.
7. In a typewriter, the combination with a platen, a traveling carriage for type-spacing said platen, and a guide-frame for said 110 carriage comprising front and rear carriage-supporting members, of a line-end alarm comprising a bell mounted between said members, a clapper for said bell, a support for said clapper, comprising a resilient member secured at one end to one of said carriage-supporting members and supporting said clapper at its other end within striking distance of said bell, a line-end-determining finger carried by said carriage, 115 and a tappet carried by said bell-clapper and projecting through the opposite carriage-supporting member into the path of said finger, so as to be engaged and released thereby to ring said bell when said 120 carriage reaches the line-end position determined by the position of said finger on said carriage.
8. In a typewriter, the combination with a platen, a traveling carriage for type-spac- 130

ing said platen, and a guide-frame for said carriage comprising front and rear carriage-supporting members, of a line-end alarm comprising a bell mounted between 5 said members and secured to one of them, a clapper for said bell, a support for said clapper, comprising a resilient member secured at one end to the opposite one of said carriage-supporting members and having 10 its clapper-supporting end passed through an opening in said bell, a line-end-determining finger carried by said carriage, and a tappet carried by said bell-clapper and projecting into the path of said finger, 15 so as to be engaged and released thereby to ring said bell when said carriage reaches the line-end position determined by the position of said finger on said carriage.

9. The combination, with a platen, of a 20 paper-finger to coöperate therewith, a support for said finger, the mounting of said finger upon said support being such as to permit said finger to be moved therealong in a direction parallel with the axis of said 25 platen, means for establishing a locked relation between said finger and said support at any one of a plurality of positions relative to said platen, and means normally tending to render said locking means effective so as to maintain said parts in locked 30 relation when said finger is in any one of said positions, said locking means being rendered ineffective by a tilting movement of said finger in the plane in which it is 35 movable along said support whereby, on application of pressure to the end of said finger in the direction of its movement from one of said positions to another, it may first

be tilted to render said locking means ineffective, and, by continued application of 40 such pressure, moved along said support to an adjusted position in which it will again be locked.

10. The combination, with a platen, of a paper-finger to coöperate therewith, a support for said finger, the mounting of said finger upon said support being such as to permit said finger to be moved therealong in a plane parallel with the axis of said platen in either direction, means for establishing a 45 locked relation between said finger and said support at any one of a plurality of positions relative to said platen, and means normally tending to render said locking means effective so as to maintain said parts 50 in locked relation when said finger is in any one of said positions, said locking means being rendered ineffective by either a clockwise or a counter-clockwise tilting movement of said finger in the plane in 55 which it is movable along said support, whereby, on application of pressure to the end of said finger in either of its two directions of movement along said platen, it may first be tilted to render said locking means ineffective, and, by continued application of such pressure, moved along said support to an adjusted position in which it will again be locked.

FRANCIS O. BURRIDGE,
*Executor of the last will and testament of
Lee S. Burridge, deceased.*
